UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A STANDARD FOR PLOWS.

SPECIFICATION forming part of Design No. 32,129, dated January 23, 1900.

Application filed December 2, 1899. Serial No. 739,048. Term of patent 14 years.

To all whom it may concern:

Be it known that I, GEORGE W. REAM, a citizen of the United States, residing at Canton, in the county of Stark and State of Ohio, have **5** invented and produced a new and original design for a Standard for Plows, of which the following is a specification.

In the accompanying drawings, Figure 1 is a side elevation; Fig. 2, a plan view; Fig. 3, **10** a front view, and Fig. 4 is an elevation showing the side opposite to Fig. 1.

The leading feature of the design is in the outline shape and surface configuration of the standard.

15 A represents a plain surface bordered by a projecting flange *a* following the contour of the part A, this flange being of varying depth,

greatest at the top and sides near the top and of less depth near the lower end. The opposite face is shown at B, Fig. 4. This is approximately plain, except that it has a flange across the top and for a slight distance down each side, as at *b*. A projection *c* extends rearwardly and upwardly from the rear edge of the standard, and this projection is of the **25** configuration shown. Figs. 2 and 3 show the shape from a plan and front view.

I claim—

The design for a plow-standard as herein shown and described.

GEORGE W. REAM.
